ATTORNEYS.

UNITED STATES PATENT OFFICE

BERTRAM R. SWEET, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS

SPINDLE

Application filed September 26, 1928. Serial No. 308,400.

This invention relates to spindles used in spinning or twisting yarn and relates more particularly to the heavy type of spindle commonly used in twisting operations. Such 5 spindles are required to carry relatively heavy spools or bobbins and all parts of the spindle must be of correspondingly heavy construction, with extended bearing surfaces.

It is the common practice in spindle construction to mount the blade or shaft of a spinning or twisting spindle in a long sleeve, commonly termed a "bolster", which fits more or less snugly in a cast iron spindle base or bolster casing which is secured to the spindle 15 rail.

It is one object of my invention to improve the bearings of a spinning or twisting spindle by providing a two-piece bolster, the upper portion preferably having a straight bearing 20 for the cylindrical middle portion of the spindle blade and the lower portion preferably providing a tapered step bearing for the lower end of the spindle blade.

I also provide increased oil storage in a 25 spinning or twisting spindle and make more effective provision for the circulation of oil therethrough.

An important feature of the invention also relates to the provision of an improved step 30 or thrust bearing for the lower end of the spindle.

My invention further relates to arrangements and combinations of parts which will be hereinafter described and more particularly pointed out in the appended claim.

A preferred form of the invention is shown in the drawings in which—

Fig. 1 is a vertical sectional view of my improved spindle;

Fig. 2 is a front elevation of the upper bolster member;

Fig. 3 is a front elevation of the lower bolster member;

Fig. 4 is a sectional plan view, taken along 45 the line 4—4 in Fig. 1; and

Fig. 5 is a side elevation of the spindle step.

Referring to the drawings, I have shown parts of a spindle comprising a blade 10 having a driving whirl 11 secured thereon. The 50 blade 10 rotates in an upper bolster member

12 and a lower bolster member 13, said members 12 and 13 being nonrotatably mounted in a spindle base or bolster casing 15. The base or casing is threaded at 16 to receive a nut by which it may be clamped to a spindle rail. 55

The base 15 is provided with a vertical opening 17 to receive the bolster members 12 and 13, and a slot or guideway 18 is formed in the upper part of the opening 17 to receive keys 19 and 20, inserted in the bolster members 12 and 13. 60

The upper bolster member 12 is provided with a flange 12^a adapted to be seated on an inclined surface 21 of the base 15 and by which the member 12 is vertically positioned. 65 The lower bolster member 13 engages a central projection 22 in the bottom of the opening 17 and is thereby vertically positioned.

An oil passage 25 connects at its lower end with the opening 17 in the spindle base and is closed at its upper end by a cap 26, which also acts as a doffer guard and is provided with a projecting portion 27 overlying the flange 28 on the whirl 11. 70

The blade 10 is provided with a cylindrical bearing portion 10^a intermediate its length, and with a tapered lower end portion 10^b. The lower end of the spindle blade preferably terminates in a flattened conical portion 30, engaging a hardened step 31 mounted in the lower end of the bolster member 13 and preferably flattened at its upper end as indicated in Fig. 5. 75

The lower bolster member 13 is provided with a tapered bearing portion 32 engaging the lower end portion 10^b of the spindle blade and is recessed as indicated at 33 above said bearing portion 32 to permit free circulation of oil through the spindle base 15. Slots 34 are preferably cut at opposite sides of the member 13 adjacent the tapered bearing 32 for the purpose of facilitating the circulation of oil and the dislodgment of any dirt or grit which might find its way into the spindle bearing. 85

The upper bolster member 12 has a straight cylindrical opening therethrough providing a bearing for the cylindrical blade portion 10^a. It will be noted that the bolster members 12 and 13 are spaced substantially apart ver- 100

tically, providing an oil storage space 36 between said members, with which space the oil passage 25 directly communicates.

The bolster member 12 is provided with one or more vertically extending grooves 40 (Fig. 2) and the lower bolster member 13 is provided with one or more similar grooves 41 in its upper portion, said grooves 40 and 41 also facilitating the circulation of oil through the spindle bearing.

Having described the details of construction of my improved spindle, the advantages thereof will be readily understood. The two-piece construction may be manufactured much more accurately than the one-piece bolster with its very long bored hole which was found to be extremely difficult to produce with a straight axis.

Furthermore, the separation of the upper and lower bolster members greatly improves the oil circulation through the spindle, and the provision of the hardened steel step 31 in a spindle of this type greatly reduces the wear at the lower end of the spindle. It is found that spindles manufactured as herein described run very accurately and maintain their accuracy of operation for a long period of time.

Having thus described my invention and the advantages thereof, I do not wish to be limited to the details herein disclosed, otherwise than as set forth in the claim, but what I claim is:—

In a spindle construction, a spindle base having a vertically extending opening therein, a spindle blade, a two-piece bolster providing upper and lower bearings for said blade, the lower bolster member having a tapered bearing for the lower end portion of the spindle blade, and a hardened step mounted in said lower bolster member and forming an end thrust bearing for said spindle blade.

In testimony whereof I have hereunto affixed my signature.
